DESIGN FOR A FONT OF PRINTING TYPE

Samu-El Ish-Shalom, New York, N. Y., assignor to Mergenthaler Linotype Company, a corporation

Application December 30, 1937, Serial No. 73,979

Term of patent 14 years

To all whom it may concern:

Be it known that I, Samu-El Ish-Shalom, a citizen of the United States, residing in the city of New York, in the State of New York, have invented a new, original, and ornamental Design for a Font of Printing Type, of which the following is a specification, reference being had to the accompanying drawing, forming a part thereof.

The drawing is a face view of the printing type embodying my new design. The design is characterized by the solid body of the characters as shown.

I claim:

The ornamental design for a font of printing type, substantially as shown and described.

SAMU-EL ISH-SHALOM.
